UNITED STATES PATENT OFFICE.

MAYER JONES AND BENJAMIN E. GOLDSTEIN, OF BROOKLYN, NEW YORK, ASSIGNEES
TO JONES BROS. CO., INC., OF NEW YORK, N. Y., A CORPORATION OF NEW YORK.

DESIGN FOR A CONTAINER FOR CANDY AND OTHER ARTICLES.

Application filed October 12, 1926. Serial No. 19,312. Term of patent 14 years.

To all whom it may concern:

Be it known that we, MAYER JONES and BENJAMIN E. GOLDSTEIN, citizens of the United States, and respectively residing in Brooklyn, county of Kings, city and State of New York, have invented a new, original, and ornamental Design for Container for Candy and Other Articles, of which the following is a specification, reference being had to the accompanying drawing, forming a part thereof.

We claim:

The ornamental design for a container for candy and other articles as shown.

BENJAMIN E. GOLDSTEIN.
MAYER JONES.
